UNITED STATES PATENT OFFICE.

JAMES B. MICHENER AND TOBIAS L. VARNS, OF KOKOMO, INDIANA.

GRAIN-METER.

SPECIFICATION forming part of Letters Patent No. 444,709, dated January 13, 1891.

Application filed March 26, 1889. Serial No. 304,889. (No model.)

To all whom it may concern:

Be it known that we, JAMES B. MICHENER and TOBIAS L. VARNS, citizens of the United States, residing at Kokomo, in the county of 5 Howard and State of Indiana, have invented certain new and useful Improvements in Grain-Meters; and we do hereby declare the following to be a full, clear, and exact description of the invention, such as will enable others 10 skilled in the art to which it appertains to make and use the same.

This invention relates to improvements in grain-meters, the object of the invention being, primarily, to provide an apparatus which 15 shall be simple and durable in construction and effective and accurate in operation, and which will automatically measure, weigh, and register the number of bushels of grain (or number of pounds, as desired) as it is received from the discharge-spout of a thrasher, 20 corn-sheller, bin, elevator, separator, or other source, and to discharge said grain after weighing into a bag, wagon, or other receptacle.

Another object of this invention is to so 25 construct and arrange the grain-weighing box or receptacle that when one compartment is filled sufficiently to overcome the requisite weight it will quickly turn, bringing another compartment into position instantly, to be 30 filled while the one already filled is discharging its contents, and whereby access to the filled compartment is at once cut off to prevent overfilling.

Another object of the invention is to so 35 construct and arrange a delivering-spout for the grain-meter that the same may be made to discharge at either side of the machine at will.

The invention consists in certain details of 40 construction, and in the combination and arrangement of the several parts of the grain-meter, substantially as hereinafter fully set forth and claimed.

Figure 1 represents in perspective a grain-meter constructed in accordance with this 45 invention; Fig. 2, a detail in front view of a portion of the grain-meter, parts being broken away; Fig. 3, a detail in plan view of the scale-beam and bearings therefor.

The frame or casing A of the grain-meter 50 is constructed in the shape of a square box

having an opening in the bottom through which the grain is discharged after being weighed, and an opening in the top, into which a delivering-spout a' is inserted, and through 55 which the grain is introduced into the machine from the separator, thrasher, or other source, said frame or casing consisting of the box-like portion A, secured in a more or less elevated position between uprights or standards a², which form the supports therefor.

Located within the walls of the casing A is a grain-measuring box or receptacle B, which box will preferably be semicircular or circular in construction and divided by radiating 65 partitions b' into grain-compartments b², herein shown as two in number, the box B being shown as semicircular. This compartment-box B is pivoted centrally by means of trunnions b³ to one end c' of a scale-beam C, suitably graduated, which scale-beam is fulcrumed at c² on trunnions secured to the front and back boards of the box A. This scale-beam, as clearly shown Figs. 1 and 3, is U-shaped, and is looped or doubled at one end to form an 70 elongated eye c³ at the graduated end, upon the outer arm of which loop is movably secured the weight c⁴, the bearings for the trunnions b³ and c³ being formed in the inner arm. The outer arm of the loop c³ will have suitable 75 graduating-marks thereon to determine the position of the weight when measuring different kinds of grain.

Pivoted below the bottom opening in the box A and below the line of discharge of the 85 grain-measuring receptacle B is a two-way delivery-spout D, which spout is pivotally supported by suitable metal straps d', pivoted in turn to a cross-piece upon the standards a² at each side of the machine. This 90 spout D has a large opening d² in its top centrally of a length sufficient to bring it beneath the opening in the box A in its either position, it also having offsets d³ in its either end at the terminus of said central opening to engage with the lower edge of the front and back boards of the box A to bring the closed or covered portion of the spout in close contact therewith when inclined to prevent the escape of grain.

Hinged to the front and rear sides of the machine are sheet-metal hoods E, which close

the openings in the top of the spout, as shown in Fig. 1, and prevent the escape of grain and the entrance of dirt.

As will be noticed, the spout D when being changed in position so as to deliver from the opposite side, the delivering end is carried forward as well as downward, the said spout turning on its supporting-straps, which in turn oscillate on their pivots.

Secured to each side of the box A, upon the interior and just below the cover of the box, is a spring-metal bar F, which bar is secured at its rear end only by suitable bolts and has its front end bent inward, so as to be considerably remote from the side to which it is secured, and connecting these two bars F is a flat sheet-metal strap F', having a projection f² formed upon its outer edge near the center, which projection forms a catch to be engaged by the hook-shaped ends g of a catch-bar G, secured to the front of the compartment grain-measuring receptacle B.

As shown in the drawings, (see Figs. 1 and 2,) the receptacle B is provided with but one catch-bar, which has its two ends bifurcated and hook-shaped and projected beyond the periphery of said receptacle in proper position to engage the spring-catch f² during its movements. It is obvious, however, that two or more catch-bars or equivalents might be used—as, for instance, would be necessary if the receptacle B were made circular instead of semicircular, as shown.

The system of spring-catch and spring-supports therefor herein shown and described obviates jarring strains upon the machine proper, both vertically and laterally, and secures an elastic cushion for the grain-receptacle as it alters its position.

As will be noticed by reference to the drawings, Fig. 2, the pivotal point of the receptacle B, while it is central with relation to its width, is somewhat above the bottom thereof, which in the locked position of the receptacle, or in the position illustrated in the drawings, Fig. 2, brings the center of gravity at the right of the pivotal point, and consequently when filled the same will turn to the right, bringing the left-hand compartment into position, and vice versa, thus oscillating and bringing the two compartments alternately into proper position.

This construction of grain-measuring receptacle is preferable; but should it be desired to employ a circular receptacle the catch-bars and catches will be arranged somewhat differently, they being arranged to catch when the receptacle is rotated in one direction at one side and in the other at the other side of the said receptacle.

An elongated slot h is formed in the front

and back board of the box A, where the trunnions b³ engage the scale-beam to allow downward and upward movement of the said trunnions and pivoted receptacle.

Stops h² h³ are secured to the side of the box A to gage the movement of the scale-beam.

It will be seen that requisite weight to change the position of the receptacle B may be quickly altered by sliding the weight at a greater or less distance from the fulcrum of the scale-beam.

Secured to the forward end, preferably, of the scale-beam is a compound lever h⁴, having a hook-shaped end to engage a ratchet-toothed wheel of an indicator H, secured to the front of the machine, which indicator registers the number of bushels or pounds delivered. This indicator may be of any suitable construction, the main object being to operate it directly from the scale-beam.

We claim—

1. The combination, in a grain-meter, with the casing A, of the grain-measuring receptacle B, divided into compartments mounted upon one portion of a scale-beam, the catch-bars G therein, the spring-metal strap F', having a catch thereon and adapted to yield vertically, and the spring-metal supporting-bars F therefor, adapted to yield horizontally and secured to the casing, substantially as described.

2. In a grain-meter, the combination, with the grain-receptacle B, of the U-shaped scale-beam C, fulcrumed in the frame-work and having its forward end looped to form the elongated eye c³, with the sliding weight thereon, a jointed lever pivoted to the forward end of the loop c³, and a registering device secured to the frame, to be operated by said lever as the end of the scale-beam is raised or lowered by the weight of the grain-receptacle, substantially as shown and described.

3. In a grain-meter, the combination, with the casing and grain-receptacle, of two vertically-arranged and horizontally-yielding springs secured on each side of the casing, a horizontally-arranged and vertically-yielding spring-bar secured to said springs and having notches or projections thereon, and catches secured to the grain-receptacle to engage said spring-bar, substantially as shown and described.

In testimony whereof we affix our signatures in presence of two witnesses.

JAMES B. MICHENER.
TOBIAS L. VARN.
